BRUSH FERRULE

Frederick M. Vonnegut, San Bruno, Calif.

Application April 29, 1946, Serial No. 665,738

8 Claims. (Cl. 15—191)

1

This invention relates to brushes, and more particularly to means for fastening the component parts thereof together.

An object of the invention is to provide a brush of the paint brush variety having novel means for fastening the handle and ferrule thereof together.

Another object of the invention is to provide a paint brush having fastening means on the ferrule adapted to be secured in complementary receiving means on the brush handle.

A further object of the invention is to provide a brush having simple and efficient means for fastening the ferrule to the handle so as to secure rigidity of brush construction and to maintain such rigidity during the usable life period of the brush.

Other objects and advantages of the invention will be apparent from the following description taken in conjunction with the drawing forming part of this specification and in which:

Figure 1 is a vertical sectional view of a completely assembled open center type brush embodying the novel brush and ferrule fastening means of the invention;

Figure 2 is a view in perspective of the ferrule alone;

Figure 3 is a view in perspective of the brush handle alone; and

Figure 4 is a vertical sectional view of a completely assembled closed center type brush embodying the ferrule and handle fastening means of the invention.

Referring to the drawings for more specific details of the invention, Figure 1 illustrates a completely assembled paint brush having a handle 10, a ferrule 12, bristles 14, a cement composition 16 impregnating the butt ends of the bristles 14 and adapted to secure the bristles to the ferrule 12 and to a wedged plug 18 driven between the rows of bristles 14 to provide therebetween a space 20.

This invention is no concerned with the manner of securing the bristles to the ferrule 16 or the spacing of said bristles by the plug 18, the manner of so doing being conventional and well known in the art, but, rather, to the manner in which the brush handle 10 is secured to the ferrule 12.

The handle 10, as shown in Figure 3, comprises a gripping portion 22 which may be flat or beavertailed in shape and a head portion 24 having oppositely disposed grooves 26 extending the length of the sides thereof.

The ferrule, more particularly shown in Figure

2, comprises an elongated cup portion 28 having straight sides 30, rounded ends 32, and a shoulder 34 encompassing an elongated slot 36 centrally arranged with respect to the ferrule. A pair of spaced vertical plates 38, parallel to each other and arranged at the sides of the slot 36, have at their extreme ends inwardly turned flange portions 40.

The head portion 24 of the handle 10 is connected to the ferrule 12 by an endwise insertion, or longitudinal sliding of said portion between the unconnected ends of the vertical plates 38 so that the flanges 40 of said plates are received within the grooves 26 of the handle. The handle and ferrule are thus secured together to prevent any wobbling action between said members, and the prevention of any relative longitudinal movement between the handle and ferrule is prevented by the passing of tacks or nails 42 through plate members 38 into the head of the handle.

The insertion of the impregnated butt ends of the bristles 14 into the ferrule 12 and the wedging of plug 18 between the rows of bristles 14 may either precede or follow the fastening of the handle to the ferrule, and after said insertion the sides 30 of the ferrule 12 are preferably pressed inwardly, as shown in Figure 1, to more firmly retain the bristles within the ferrule.

The ferrule 12 is preferably made of a light metal, such as aluminum, by a die casting process to impart sufficient strength to the plates 38 of the ferrule so as to prevent any bending of said plates with respect to the cut portion 28 of the ferrule during normal use of the brush.

A modification of the disposition of the bristles 14 of the brush to achieve what is known as a solid center brush is indicated in Figure 4 wherein two plugs 18 are used in combination with the side walls 30 of the ferrule 12 to separate the butt ends of three rows of bristles. In this modification of the completely assembled paint brush, the sides 30 of the cut portion 28 of the ferrule are inclined inwardly to a slightly greater extent than in the hollow center brush of Figure 1 to impart the proper lines and stiffness to the bristles.

While the preferred embodiment of the invention has been shown and described, it is understood that modifications in this embodiment may be made within the spirit of the invention and the scope of the appended claims.

What I claim as new and desire to secure by Letters Patent is:

1. In combination, a brush ferrule comprising an elongated cup having sides and a base, a pair

of spaced plates extending from the base, a flange on each plate, a handle having a head portion, and grooves in the head portion receiving the flanges of the plates, said plates being unconnected at their ends to allow for an endwise insertion of the head portion of the handle between said plates.

2. In combination, a unitary brush ferrule comprising an elongated cup having sides and a base, a pair of spaced plates extending from the base, 10 a flange on each plate, a handle having a head portion, and grooves in the head portion receiving the flanges of the plates, said plates being unconnected at their ends to allow for an endwise insertion of the head portion of the handle be- 15 tween said plates.

3. In combination, a unitary brush ferrule comprising an elongated cup having sides and a base, a pair of spaced parallel plates extending from the base, a flange on the end of each plate, a 20 handle having a head portion between the plates, and grooves in the head portion receiving the flanges of the plates, said plates being unconnected at their ends to allow for an endwise insertion of the head portion of the handle be- 25 tween said plates.

4. In combination, a unitary brush ferrule comprising an elongated cup having sides and a base, a pair of spaced parallel plates extending from the base normal thereto, a flange on the end of each plate extending inwardly of the plate, a 30 handle having a head portion between the plates, and a groove in each side of the head portion in oppositely disposed relation enclosing therein the flanges of the plates, to secure the handle against longitudinal movement with respect to the ferrule, said plates being unconnected at their ends to allow for an endwise insertion of the head portion of the handle between said plates.

5. In combination, a unitary brush ferrule comprising an elongated cup having sides and a base, a slot in the base medially thereof, a pair of rigid parallel plates normal to the base spaced apart by the slot, a flange on the end of each plate extending inwardly of the plates, a handle having 45 a head portion between the plates in contact therewith, and a groove in each side of the head portion in oppositely disposed relation receiving therein the flanges of the plate, said plates being unconnected at their ends to allow for an endwise insertion of the head portion of the handle between said plates.

6. In combination, a unitary brush ferrule comprising an elongated cup having parallel sides, rounded ends, and a base normal to the sides 55 and ends, a rectangular slot through the base,

medially thereof, a rigid plate normal to the base in each of the long sides of the slot, said plates being unconnected at their ends and being oppositely directed from the base with respect to the sides and ends of the cup, a flange on the end of each plate extending inwardly of the plate, a handle having a head portion between the plates and in contact therewith, a groove in each side of the head portion in oppositely disposed relation receiving therein the flanges of the plates, and means securing the plates to the head portion to prevent relatively longitudinal movement therebetween.

7. In combination, a brush comprising a unitary ferrule having the bristles secured therein, said ferrule having integral base and side walls forming a cup, a pair of rigid parallel plates spaced apart normal to the base and oppositely directed therefrom with respect to the side walls, said plates being unconnected at their ends, a flange on the end of each plate extending inwardly of the plates, a handle comprising a head portion, a groove in the head portion on each side thereof, said groove having fitted therein the flanges of the plates, and a tack through each plate into the head portion of the handle.

8. In combination, a brush comprising a unitary ferrule having the bristles secured therein, said ferrule having integral base and side walls forming a cup, a rectangular slot medially of the base, a pair of rigid parallel plates, conterminous with respect to the long sides of said slot and spaced apart the width of the slot, normal to the base, and oppositely directed therefrom with respect to the side walls, a flange on the end of each plate extending inwardly of the plates, a handle for the brush comprising a head portion, a groove in the head portion on each side thereof, said groove having fitted therein the flanges of the plate, and a tack through each plate into the head portion of the handle.
